UNITED STATES PATENT OFFICE

LOREN A. HART, OF CHARLEVOIX, MICHIGAN

AUTOMATIC AIR MIXING APPARATUS FOR INTERNAL COMBUSTION MOTORS

Application filed June 21, 1928. Serial No. 287,310.

The principal object of this invention is to provide an automatic air mixing apparatus for internal combustion motors that will furnish the proper amount of air into the intake manifold to be mixed with the fuel charge, regardless of the speed of the motor.

A further object of this invention is to provide an automatic air mixing apparatus for internal combustion motors that cracks up and gasifies the heavier oils in our present day gasoline as well as low test fuel oils, which would otherwise enter the cylinder in uncracked globules suspended in the air.

15 A still further object of this invention is to provide an air mixing device that does not obstruct the passageway of the intake manifold, thereby reducing the amount of the fuel charge that passes through the same.

20 A still further object of this invention is to provide an air mixing device that is easily and readily attached without the services of a skilled mechanic.

A still further object of this invention is 25 to provide an automatic air inlet apparatus for intake manifolds that is economical in manufacture and durable and efficient in use.

These and other objects will be apparent 30 to those skilled in the art.

My invention consists in the construction, arrangement and combination of the various parts of the device, whereby the objects contemplated are attained as hereinafter more 35 fully set forth, pointed out in my claims and illustrated in the accompanying drawings, in which:

Fig. 1 is a side view of an internal combustion motor with my device threaded into the 40 intake manifold and ready for use.

Fig. 2 is a side sectional view of my invention and more fully illustrates its construction.

Fig. 3 is a side view of the device secured 45 to an intake manifold and is taken on line 3-3 of Fig. 1.

By scientific tests it has been found that when the motor is turning over very slowly, little if any air should be permitted to enter 50 the fuel charge, and when it is revolving at

a high speed a great quantity of air should enter the manifold. This mistake by previous designers was due to lack of knowledge of the fact that the suction in the intake manifold was greater when the motor was running slow than when it was running fast. It is with the above in view that I have created my automatic air mixing apparatus.

I have designated the intake manifold of an ordinary internal combustion motor by the numeral 10 having the carburetor 11. In Fig. 1, I have designated my device generally by the numeral 12, which is threaded into the manifold 10 as near to the carburetor as is practicable. The body of my device is designated by the numeral 13, having the reduced end 14 designed to be threaded into the intake manifold as shown in Fig. 3. The numeral 15 designates a longitudinal bore in the end portion of the body 13, adjacent the reduced end. The numeral 16 designates a passageway in the reduced end portion communicating with the bore 15 and the outside atmosphere. Communicating with the bore 15 is a second longitudinal bore 17, as shown in Fig. 2. This last mentioned bore leaves the opposite end of the body 13 open as will be noted. Threaded into this bore 17 is the cap member 18 having the hole 19. The numeral 20 designates a hole in the side of the body member 13, communicating with the bore 15 and in relatively close proximity to the reduced end portion. Slidably mounted in the bore 15 is the piston member 21 capable of moving to a position that closes the hole 20.

Formed on the rear end of the piston 21 and inside the bore 17 is the head portion 22. Embracing the piston 21, engaging the head 22 and the shoulder 23 in the casing is the coil spring 24 for yieldingly holding the piston in the rear portion of the body 13. The shoulder 23 slopes inwardly toward the passageway 16, as shown in Fig. 2 providing an air-tight fit when the piston 21 is pulled into engagement with the same. The tapered forward end 26 of the piston is formed not only to conform to the sloping shoulder of valve seat 25, but when passing the passageway 20, to open and close that opening gradually.

To install the invention it is merely neces-

sary to drill a hole in the intake manifold, tap and same, then screw the reduced end portion of the device into the hole. The position of this hole in the intake manifold may 5 be any location, but preferably as close to the carburetor as possible. To adjust the device to the motor to which it is attached, the motor is first throttled to a very slow speed, and the light coil spring is pulled apart or compressed 10 by the fingers or pliers until its resiliency is such that the suction in the manifold will pull the piston forward in its bore and close the hole 20 thereby preventing any air to enter the manifold when the motor is running 15 slowly. As soon as the motor is speeded up the suction in the manifold will be reduced and the piston will be allowed to slide backwardly in the bore to a position where air may enter through the hole 20 and pass into 20 the manifold. The faster the motor runs the more air is required for its proper functioning. As no part of the device extends into the passageway of the intake manifold the area of that passageway will not be affected. 25 As we have seen the successful functioning of the device at various motor speeds depends on the proper reciprocation of the piston. This reciprocation is automatically obtained by the suction in the manifold when 30 the motor is rotating very slowly, and the lack of enough suction to compress the spring 24 when the motor is turning over very rapidly. The spring 24 moves the piston to the rear when little vacuum exists at the forward end of the piston and when a sufficient vacuum does exist forward of the piston, the atmospheric pressure engaging the head 22 will force the piston forwardly against the coil spring 24 and close the passageway 20. 35 The hole 19 makes it possible for the outside atmosphere to contact the rear side of the member 22 and also permits air to escape when the piston is moved to the rear by the spring 24. To clean the device, or to remove the piston 40 and spring it is merely necessary to unscrew the cap member 18. By the air entering the manifold in a transverse flow to the flow of the fuel charge, a vortex will be created that aids in the cracking up and gasifying of the fuel mixture. Once the device is 45 installed it requires no further attention, and adds to the power of the motor and reduces fuel consumption.

Some changes may be made in the construction and arrangement of my apparatus without departing from the real spirit and purpose of my invention, and it is my intention to cover by my claims any modified forms of structure or use of mechanical equivalents which may be reasonably included within their scope.

I claim:

1. In a device of the class described, a body member designed to be screwed into 55 the intake manifold of an internal combus-

tion motor, a bore in said body member communicating with the inside of said manifold, a second bore in the rear portion of said body member communicating with the first mentioned bore, a shoulder in said last mentioned bore, a passageway in said body member communicating with the outside atmosphere and the first mentioned bore, a piston slidably mounted in said bores, a head formed on the rear end of said piston, and a coil spring embracing said piston and engaging said head and said shoulder. 70

2. In a device of the class described, a body member designed to be threaded into the intake manifold of an internal combustion motor, a bore in said body member communicating with the inside of said manifold, a second bore in the rear portion of said body member of greater diameter than said first mentioned bore; and communicating 80 with said first mentioned bore, a piston slidably mounted in said bores, a head formed on the rear end of said piston and in said second bore and of greater diameter than said first bore, a coil spring around said piston and having one end engaging said head and its other end engaging the shoulder created by said first and second bores, and a passageway in said body communicating with the outside atmosphere and the said first mentioned 90 bore. 95

3. In a device of the class described, a body member designed to be screwed into the intake manifold of an internal combustion motor, a bore in said body member communicating with the inside of the said manifold, an air inlet leading into said bore, a second bore communicating with the first bore and leaving the rear end of the body member open, a shoulder formed in said second bore, a piston slidably mounted in said bores, a head formed on the rear end of said piston, a coil spring embracing said piston and engaging said head and said shoulder, and a cap member having an opening for 100 inclosing said second bore. 105

4. In a device of the class described, a body member designed to be screwed into the intake manifold of an internal combustion motor, a bore in said body member communicating with the inside of the said manifold, an air inlet leading into said bore, a second bore communicating with the first bore and leaving the rear end of the body member open, a shoulder in said body member and at the forward end of said second bore, a piston slidably mounted in said bores, a head formed on the rear end of said piston, a coil spring embracing said piston and engaging said head and said shoulder, and a detachable cap member having an opening for 110 inclosing said second bore. 115

5. In a device of the class described, a body member designed to be screwed into 120

the intake manifold of the internal combustion motor, a bore in said body member, a small passageway in the end of said body member that is threaded into said manifold
5 communicating with said bore and the inside of the said intake manifold, a forwardly and inwardly sloping shoulder around said passageway and at the forward end of said bore, a passageway in said body member communicating with the outside atmosphere and said bore, a second bore in the rear portion of said body member communicating with the first mentioned bore, a shoulder at the forward end of said second bore, a passageway in said body member communicating with the outside atmosphere and the second mentioned bore, a piston slidably mounted in said bore, a tapered end formed on said piston capable of engaging said shoulder at
20 the forward end of said first mentioned bore, a head formed on the rear end of said piston, and a coil spring embracing said piston and engaging said head and the said shoulder at the forward end of said second bore.
